UNITED STATES PATENT OFFICE.

SAMUEL N. PRATHER AND LOUIS H. BOHN, OF ALLEGHENY, PENNSYLVANIA.

GAS-BURNER.

SPECIFICATION forming part of Letters Patent No. 451,517, dated May 5, 1891.

Application filed July 9, 1890. Serial No. 358,182. (No model.)

To all whom it may concern:

Be it known that we, SAMUEL N. PRATHER and LOUIS H. BOHN, of Allegheny city, in the county of Allegheny and State of Pennsylvania,

have invented a new and useful Improvement in Gas-Burners, of which the following is a full, clear, and exact description, reference being had to the accompanying drawings, forming part of this specification, in which—

Figure 1 is a front elevation of our improved gas-burner. Fig. 2 is a vertical section on the line II II of Fig. 1.

In the drawings, 2 represents the upright gas-chamber of the burner, which consists of a hollow chamber made widest and with an offset at the base and tapering in thickness toward the top and above said offset or shoulder. The chamber so formed at the base of the burner is of material advantage, as it checks the flow of gas, allows the proper intermingling of the air therewith, and prevents the combustible mixture from rising directly and in a body to the upper outlets of the burner, also serving to change the currents so that the combustible mixture of air and gas escapes with substantially uniform pressure at each and all the several outlets of the burner.

3 is the gas-supply pipe, which enters the chamber 2 through an air-mixing chamber 4, which may be of usual construction. The face *b* of the chamber 2 is perforated with a number of small holes *c* for the outlet of gas. 5 is an upright plate or partition, which is set in front of the burner-plate 2 at the base thereof, and 6 are air-inlets at the base of the intermediate space or flue *e*. The plate 5 is preferably adjustable to and from the face of the burner, and may be made of mica or other transparent material set in a suitable inclosing-frame, as shown in the drawings.

In the use of the burner the gas escapes from the perforations in the face-plate and burns thereat. The portion of gas which escapes from the perforations back of the plate 5 passes upwardly, as indicated by the arrows, inducing with it a supply of air from the perforations 6, and has the effect of bettering the combustion, increasing the heat given by all the gas-jets above the top of the plate 5, and by creating a direct upward draft along the face of the plate causing them to

burn in a broad sheet of flame. The advantages of the burner in this regard have been demonstrated by its practical and successful use.

Our invention consists in the combination, with a vertical burner having a series of gas-outlets at different levels, of a vertical plate arranged in front thereof and extending up in front of the lower part or base of said burner to form a flue in front of and at the base of the burner, whereby the gas is caused to burn in a bright uniform sheet over the whole face of the burner.

Our burner is especially desirable for use in burning natural gas, though it may be employed in burning manufactured gas also. It may be used in a grate or open fire-place, or may be burned as an open burner for heating rooms. In construction, form, and relative arrangement of the parts it may be modified in divers ways.

We claim—

1. The combination, with a gas-burner having an upright face, of an upright plate arranged in front thereof and at a short distance therefrom at the base, said burner having in its face series of gas-outlets arranged on different levels extending above the said plate, substantially as and for the purposes described.

2. The combination, with an upright or vertical burner having a series of gas-outlets arranged on different levels from bottom to top thereof, of a sliding or adjustable plate arranged in front of said burners and extending up to a point above the lower series of gas-outlets of the burner, substantially as and for the purposes specified.

3. The combination, with an upright or vertical gas-burner having an enlarged chamber at its base and a perforated burner-face which extends up above the enlarged base of the burner, of a plate arranged in front of the perforated face of said burner and extending up to substantially the height of the enlarged base portion of the burner, substantially as and for the purposes specified.

In testimony wherof we have hereunto set our hands this 1st day of July, A. D. 1890.

SAMUEL N. PRATHER.
LOUIS H. BOHN.
